UNITED STATES PATENT OFFICE

MARKUS M. SCHWARZKOPF, OF ST. LOUIS, MISSOURI

TORCH

Application filed June 23, 1930. Serial No. 463,299.

This invention relates generally to torches and, more particularly, to a certain new and useful improvement in heating torches of the premixing type.

My invention has for one object to provide a torch in which the constituents of the combustible mixture to be burned are premixed in selected automatically uniform proportions for effecting a steady and non-variant flame of the desired characteristics.

Another object of my invention is to provide a premixing torch in which two or more fluids in separate containers are caused to mingle under controlled pressure conditions, in which compensation for diminution of volume of the fluid in one container is effected by determinable flow of fluid thereto from the other container.

Still another object of my invention is to provide a torch in which the full mixture is effectively commingled and heated for gassification or vaporization thereof.

And with the above and other objects in view, my invention resides in the novel features of form, construction, arrangement, and combination of parts hereinafter described and pointed out in the claims.

In the accompanying drawings (three sheets),—

Figure 1 is a rear elevation of a torch of my invention, portions thereof being broken away to illustrate the interior arrangement;

Figure 2 is a top plan view of the torch, the mixing head being shown in horizontal section;

Figure 3 is an enlarged fragmentary vertical section of the cover and mixing head; and

Figure 4 is a sectional view taken approximately along the line 4—4, Figure 1.

Referring now more in detail and by reference characters to the drawings, which illustrate a preferred embodiment of my invention, an outer or so-called air-container A, which includes a shell 1 having a preferably

spun annular base 2 and a bottom wall 3 brazed thereto, has its upper end threaded into, and for closure by, an annular flange 4 depending from a detachable cover or closure B, from which interiorly depends, preferably concentrically into the container A, a second annular flange 5 threadedly engaging, for closure thereof by the cover B, an inner or so-called fuel-container C, which latter includes a shell 6 having a spun shoulder 6', to which is brazed a bottom wall 7 preferably, however, upwardly spaced from the bottom wall 3 of the outer container A.

Located at a side of the container A, intermediate the walls 1 and 6, is an air pump D comprising a cylinder including a tubular barrel 8 having an upper lateral flange 9 supportingly engaged between an end of an apertured boss 10 upstanding from the cover B and a cap 11 screwed thereto, the cap 11 being suitably apertured for air admittance, as shown, and bored for the guidable reciprocation therein of a plunger 12 suitably handled at its outer end and carrying at its inner end a piston 13 having a cup-leather 14 of conventional construction for working in the barrel 8.

At its lower depending end, the barrel-walls are reflexly spun into a frusto-conical valve-seat 14 apertured at its smaller upwardly presented end or apex, as at 15, for communication interiorly with the barrel 8, over which slot 14 is interiorly disposed a star-shaped cage or spider 16 having downturned legs supportingly resting in the reflexed end of the barrel 8. The cage 16 is centrally apertured for shiftable movement therein of a plunger 17 supporting at its lower end a frusto-conical valve or leather 18 complementary to, and adapted to engage, the seat 14, the valve or leather 18 being gripped between a frusto-conical backing washer 19 and a clamping washer 20, both suitably secured to the plunger 17. The plunger 17 at its upward interior end has a

- head 21, between which and the cage 16 is seated a compression spring 22 normally upwardly urging the plunger 17 for engaging the valve 18 with the seat 14.
- 5 Air being introduced into the container A by means of the pump D, a suitable preferably liquid fuel is introduced into the container C through an aperture or filling vent 23 (Figure 1) provided in the cover B, said aperture being normally closed by a detachable cap 24 (Figure 2). Such fuel in the container C is subjected to air under pressure fed from the container A under determinable conditions of flow through a compensating valve E comprising a preferably frustoconical valve-member 25 shiftable on a rod, such as the shank of a common-screw 26, dependingly adjustably threaded into the upper wall of a valve chamber 27 communicating with the chamber A through a passage 28 cored in the cover B, said chamber 27 being preferably bored in the cover B for forming at its end an annular rim adapted for impingement by the valve-member 25, the latter being yieldingly seated under urging of a compression spring 29 embracing the screw 26 and bearing between its head and the member 25 for regulatively communicating the container A with the container C.
- 10 Depending in the container C to a point adjacent the bottom wall 7 thereof, is a feed tube 30 preferably filled with a suitable filtering medium, as cotton wicking 31, and threaded at its upper end into a cored passageway 32 provided in the cover B, said passageway extending upwardly into a valve-chamber 33 provided transversely in a mixer-head F upstanding centrally from the cover B. Another passageway 34 diagonally cored in the cover B and head F suitably communicates the container A with a valve chamber 35 provided in the head F forwardly converging towards the valve chamber 33 (Figure 2).
- 15 Suitably provided with handles 36, and forwardly threaded into the rearwardly divergent ends of the chambers 33, 35, through suitable stuffing boxes 37, are, respectively, a fuel needle-valve 38 and an air needle-valve 39 adapted to co-operatively seat into respective axial ports 33', 35' leading respectively from the chambers 33, 35, convergingly into a common mixing chamber 40 provided forwardly in the head F for controllable confluent flow of fluids from the chambers 33, 35, thereinto, said mixing-chamber being provided with preferably brass mixing-screens 41 or the like, flowably traversed by the confluent fluids for effective agitation and commingling thereof.
- 20 Such commingled fluids are preferably also subjected to suitable heating means for gasifying or vaporizing the fuel, and for such purpose the walls of the chamber 40 are exteriorly provided with lateral heating fins

or flanges, as 42, under which is provided a generating cup 43, as it may be described, formed by walls 44 upstanding from the cover B suitably for the purpose (Figure 3). The cup 43 is supplied with fuel from the container C through a port 45 forwardly opening through the head F under the mixing-chamber 40 and communicating with an end of a valve chamber 46 having, in turn, communication through a passageway 47 cored in the head F and cover B with a second capillary tube 48 dependingly threaded at an end in the passageway 47 and also extending to a point adjacent the bottom wall 7 of the container C, said tube 48 being preferably also filled with the cotton wicking 31. A needle valve 49, having a rearwardly disposed handle 49', is threaded forwardly through a stuffing-box 50 into the valve chamber 46 for co-operatively seating in the port 45 for controlling the feed of fuel to the generating cup 43.

25 The mixing-chamber 40 opens forwardly endwise from the mixing head F and has thereinto threadedly and abuttingly engaged a conic-ended burner tip 51 provided with a longitudinal bore 52 suitably at its inner end expanded and communicating with the chamber 40 for flow therefrom into and through the burner-tip 51 of the mixed and vaporized combustible fluids.

30 The particular embodiment of my invention illustrated is of the size and type commonly known as a hand-torch, and for such purpose a grip or handle 53 is suitably mounted exteriorly on the rear side of the container A oppositely from the tip 51, as will be readily understood and as best seen in Figure 2.

35 In assembling the torch, the compensating valve E is adjusted by suitably manipulating the screw 26 for tensioning the spring 29, which, urging the valve 25 on its seat at the valve chamber 27, thus predeterminedly regulates the flow of fluid from the container A to the container C responsively to drop in pressure therein to compensate for decrease of volume of the fluid in the container C, as will soon appear. However, I may say that, in a hand torch as shown, I prefer to adjust the valve E to open such that the minimal pressure in the container C is substantially one pound less than the pressure in the container A.

40 In use, the containers A and C are filled with the desired fluids to be proportionally mixed for combustible purposes, one of the fluids being preferably normally immiscible in the other. More particularly, I prefer to employ a gaseous medium, as air, in the container A, and a liquid fuel, as gasoline or the like, in the container C. However, I wish to state that, by suitable modification, such as a tube depending in the container A, of the connection between said container and the

valve chamber 35, another liquid constituent may be employed in the container A, if desired. If air and gasoline are used, the latter is introduced into the container C, and 5 air under pressure introduced into the container A by manipulation of the pump D, the pressure in the container C being raised to its said minimal pressure by flow of air thereinto through the compensating valve E from 10 the container A.

When using gasoline or like vaporizable or gasifiable fuel, as in the present instance, a sufficient or desired quantity of the fuel is introduced into the generating-cup 43 by 15 manipulation of the valve 49, and the contents of the cup 43 lighted for preheating the mixing chamber 40, the valve 49 being opened shortly before the fuel in the cup 43 is burned out, sufficiently to maintain a pilot or heating 20 flame under the chamber 40. The chamber 40 being properly heated, the fuel-needle valve 38 is employed suitably for controllably admitting the gasoline to the mixing chamber for gasification therein, and then, by means 25 of the air-needle valve 39, a sufficient amount of air, as I will shortly point out, is admitted to the mixing chamber 40 and there commingled with the fuel gas, the confluent combustible gases being ignitably discharged 30 through the burner tip 51, as described.

By properly proportioning the ratio of air to gasoline, the resulting flame from the torch may be made oxidizing, reducing, or neutral in character, and hence my invention may 35 successfully be employed for heating, cutting, or welding, as may best serve the purposes intended.

And the flame from the torch is particularly steady and uniform by reason of the 40 action of the compensating valve E, which functions efficiently and automatically for effecting a uniform ratio of pressures in the containers A and C and maintaining the selected proportionate admission of fluids 45 therefrom into the mixing chamber 40.

I might add that, for such purpose, I prefer to proportion the relative capacities of the containers A and C such that there will be a surplus of air available at all times for maintaining the fluids in the containers A and C 50 within the determined minimal pressure differences, the relative capacities of the containers A and C and the minimal difference to be maintained being selected suitably in view of the fluids to be employed. The jet-flame will not vary in its characteristics as long as there is pressure, and obviously, the intensity of a diminishing flame may be stimulated by use of air-pump D.

It is to be understood that changes and modifications in the form, construction, arrangement, and combination of the several parts of the torch may be made and substituted for those herein shown and described

without departing from the nature and principle of my invention.

Having thus described my invention, what I claim and desire to secure by Letters Patent is:

1. A torch comprising, in combination, an outer container, an inner container, a top-closure common to said containers, the closure having a port for providing communication between said containers, means comprising a biased valve for automatically regulating communication through said port between the containers, the closure having a mixing-chamber and separate communicating passages for providing communication between the respective containers and the mixing-chamber, valves for independently controlling communication through said passages between the respective containers and the mixing-chamber, and a burner-tip for directional discharge of fluid from the mixing-chamber. 70 75 80 85

2. A torch comprising, in combination, an outer container, an inner container, a top-closure common to said containers, the closure having a port for providing communication between said containers, means comprising a yieldingly adjustable valve for automatically regulating communication through said port between the containers, a mixing-chamber providing head mounted on the closure, 90 the closure and head having separate communicating passages for providing communication between the respective containers and the mixing-chamber, valves for independently controlling communication through said 95 passages between the respective containers and the mixing-chamber, and a burner-tip for directional discharge of fluid from the mixing-chamber. 100

3. A torch comprising, in combination, an outer container, an inner container, a top-closure common to said containers, the closure having a port for providing communication between said containers, means comprising a biased valve for automatically regulating communication through said port between the containers, the closure having a mixing-chamber and being provided with diagonally disposed separate passages for providing communication between the containers and the mixing-chamber, a pair of valves having divergent stems for independently controlling communication through said 105 110 115 120 125 passages between the respective containers and the mixing-chamber, and a burner-tip for directional discharge of fluid from the mixing-chamber. 120

4. A torch comprising, in combination, an outer container, an inner container, a top-closure common to said container, the closure having a port for providing communication between said containers, means comprising a biased valve for automatically regulating communication through said port between the containers, the closure having a mixing- 130

chamber and being provided with separate passages for providing communication between the containers and the mixing-chamber, valves for independently controlling communication through said passages between the respective containers and the mixing-chamber, a burner-tip for directional discharge of fluid from the mixing chamber, the closure having a generating-cup disposed under and adjacent to the mixing-chamber, and means for supplying the cup with combustible fluid from one of said containers.

In testimony whereof, I have signed my name to this specification.
